(57) **CLAIM**

The ornamental design for an apparatus for recording, transmission or processing of information, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of an apparatus for recording, transmission or processing of information showing our new design;

FIG. 2 is a front elevational view showing the design for the apparatus for recording, transmission or processing of information of FIG. 1;

FIG. 3 is a rear elevational view showing the design for the apparatus for recording, transmission or processing of information of FIG. 1;

FIG. 4 is a left side elevational view showing the design for the apparatus for recording, transmission or processing of information of FIG. 1;

FIG. 5 is a right side elevational view showing the design for the apparatus for recording, transmission or processing of information of FIG. 1;

FIG. 6 is a top plan view showing the design for the apparatus for recording, transmission or processing of information of FIG. 1; and,

FIG. 7 is a bottom plan view showing the design for the apparatus for recording, transmission or processing of information of FIG. 1.

1 Claim, 7 Drawing Sheets
